UNITED STATES PATENT OFFICE.

JOHN F. POLHEMUS, OF JOHNSON CITY, NEW YORK, ASSIGNOR TO ANSCO COMPANY,
OF BINGHAMTON, NEW YORK, A CORPORATION OF NEW YORK.

FINDER FOR CAMERAS.

1,206,372.

Specification of Letters Patent. Patented Nov. 28, 1916.

Application filed June 29, 1916. Serial No. 106,581.

To all whom it may concern:

Be it known that I, JOHN F. POLHEMUS, a citizen of the United States, and a resident of Johnson City, county of Broome, and 5 State of New York, have invented certain new and useful Improvements in Finders for Cameras, of which the following is a specification.

The merits of the so-called rotating finders 10 for photographic cameras, an example of which is shown in the patent to Shanley, No. 916,205 dated March 23, 1909, and also those of the so-called folding finders, whereby they are adapted to small folding hand 15 cameras, an example of which is shown in the patent to Bornmann, No. 1,180,252 dated April 18, 1916, are fully appreciated by the photographic public and are recognized as desirable improvements; but there has never 20 heretofore been any construction devised whereby both of these advantageous features could be availed of in the same camera.

It is the purpose, therefore, of this invention to so construct a finder and its associated and co-acting parts that the advantages of the rotating finder and also those of the folding finder may be combined in one 25 and the same camera, thus making it possible to avail of these improvements in the necessarily compact, so-called pocket cameras, the use of which in recent years has been and 30 still is rapidly increasing.

In order that the construction and method 35 of operation embodied in this present invention may be more clearly understood and the forward step beyond that shown in the two prior patents above referred to more easily appreciated, I refer to them for a more detailed exposition of that which they set 40 forth than would be proper in this present specification.

Referring to the drawings, Figure 1 is a sidewise elevation of a finder embodying this present invention; Fig. 2 is a view similar to 45 Fig. 1, showing the finder folded forwardly, thus reducing the space required for it when the camera is collapsed; Fig. 3 is a vertical sectional view taken through the middle of Fig. 1; Fig. 4 is a view partly in elevation and partly in section, the finder having been 50 tipped forwardly toward the observer, as for the taking of a horizontal picture; Fig. 5 is a vertical sectional view taken on the line 5-5 of Fig. 3; Fig. 6 is a plan view in

detail of the top lens or observation plate 55 and co-acting parts.

In the drawings, 1 represents a bracket for the support of the finder. It may be of any preferred form and is usually attached to some suitable part of the camera or lens 60 frame.

2 is the lens mount for the finder, 3 the finder lens, 4 the front plate of the finder, 5 a thin washer, which I prefer to interpose between the bracket and the front plate. 65 The front plate 4 rotates upon the exterior of the ring 6 (see below) as usual.

The lens mount may be made in any preferred manner. In the present instance, in addition to the outer threaded ring 2, it 70 comprises a ring 6, which is threaded to the ring 2 and has the usual confining ring 7. 8 is a sectional gear or gear disk, which is rigidly held against the front plate 4 by expanding outwardly the inner edge 9 of the 75 ring 6. It will be noted (see best Fig. 5) that the cogs 10 on the broken gear 8 may extend part way around the same only.

11 is the back plate for the finder. It supports the usual mirror 12. 80

13, 13, are the side plates.

14 is the top plate in which the upper or observation lens 15 is secured in any preferred manner, preferably by being held in an annular frame 16. The top plate 14 is 85 hinged to the back plate 11, as at 17, at which hinge is a spring 18, which normally when the finder is in position for use draws the top plate downwardly upon the upper edge of the front plate and similarly draws the 90 top plate against the front of the finder when the latter is folded over forwardly, as in Fig. 2, thus causing it to assume and maintain proper positions in both cases. A similar hinge 19 connects the back plate 11 95 to the lower part of the front plate or rather to flanges 20 formed thereon, one at each side. A spring 21 tends normally to throw the back plate and the parts supported by it backwardly or away from the lens 3. 100

On the lower edge of the annular frame 16, which supports the upper lens 15, I form a face gear 22 (see Fig. 5), the teeth of which mesh with the teeth of the broken gear disk 8, and circumferentially about the frame 16 105 I cut a groove 23 within which, on each side of the finder, fits a wire or rod 24, these rods being rigid and one of them (see Fig. 6) has

projecting ends 25, which serve to engage with the horns 26 at the upper ends of the side flanges of the front plate to hold the parts in proper position, all as set forth in detail in said patent to Bornmann, No. 1,180,252. The purpose of the annular groove 23 and the rods 24 fitting in them, one at each side of the frame 16, is so that when the finder is tilted from the vertical to the horizontal position and the cogs or teeth on the gear disk 8 engage in those of the face gear 22, the frame 16 bearing the upper or observation lens 15 and the diaphragm plate 27, may be given a quarter rotation, thus transferring the open or observation space of the diaphragm from the vertical to a horizontal position.

The diaphragm plate may be applied over the upper lens 15 in any preferred manner. I show it in the form of a flanged structure held in place by screws 28, 28, because if made in this form it will serve also as a confiner for the upper lens 15, and thus fulfill dual functions.

On the forward edge of the top plate, I provide a small flat spring 29, held in position by screws 30. This spring is provided at or near its center with a small stud or pin 31, which passing through a hole in the forward edge of the top plate, engages in suitable recesses 32, 32, (see best Fig. 4) made in the edge of the annular frame 16, which supports the upper lens. The purpose of this device is to act as a stop to determine when the upper lens and its diaphragm have attained proper positions for a vertical or horizontal exposure, as the case may be.

From what has already been said, the operation is obvious. During the making of a vertical exposure the parts should be in the position shown in Figs. 1 and 2. When it is desired to take a horizontal picture, the operator taking hold of the finder, turns it through a quarter circle, in so doing the teeth on the gear disk 8 engaging with the teeth on the under edge of the upper lens frame 16 cause that lens frame and the lens and diaphragm carried by it to rotate equally, that is to say, to make a quarter turn and in so doing the little projection 31 on the flat spring 29 will pass out of the depression 32 in the annular lens frame 16, in which it rested when the parts are in position for vertical exposure, and the annular frame 16 will rotate upon the rods 24 and when the lens frame 16 has completed its quarter rotation, the little stop 31 will pass into the second depression 32 in the lens frame and thus act as an indicator or stop to indicate that the diaphragm is in position for a horizontal exposure.

It will be particularly noted that the addition to the structure of the parts which assure the proper positions of the diaphragm

in the two positions of the finder in no wise interfere with the folding feature set forth in said Bornmann patent, on the contrary, all parts operate and function in this present construction precisely as they do in the said Bornmann construction and secure the beneficial results flowing therefrom. Special attention is called, however, to the fact, that the little stud 31 co-acting with its supporting spring 29 and engaging in recesses 32 made in the annular lens frame 16, will assure the rotation of that frame to proper position for reengagement between the two gears described when the finder is again unfolded or tipped backwardly into operative position, after being tipped forwardly during the folding of the camera.

It will be obvious to those who are familiar with such matters that modifications may be made in the details of construction and yet the essentials of my invention be retained. I therefore do not limit myself to such details.

I claim:

1. A finder having a rotary front plate, a back plate pivoted to the front plate, a top plate pivoted to the back plate, means to detachably hold said pivoted parts in dual positions, a stationary gear on or near the front plate, a diaphragm rotatably supported upon the top plate, and a gear connected with the diaphragm supporting structure adapted to rotate with it and which meshes into the stationary gear on the front plate.

2. A finder having a rotary front plate, a back plate pivoted to the front plate, a top plate pivoted to the back plate, means to detachably hold said pivoted parts in dual positions, a stationary gear on or near the front plate, a diaphragm rotatably supported upon the top plate, a gear connected with the diaphragm supporting structure adapted to rotate with it and which meshes into the stationary gear on the front plate, and a stop which automatically indicates the limit of the movements of the diaphragm.

3. A finder having a rotary front plate, a back plate pivoted to the front plate, a top plate pivoted to the back plate, a spring at each of said pivotal points which normally tend to throw the finder open, means on the front plate engaging means on the top plate to detachably hold the said pivoted parts against the stress of said springs, a stationary gear on or near the front plate, a diaphragm rotatably supported upon the top plate, and a gear connected with the diaphragm supporting structure and adapted to rotate with it and which meshes into the stationary gear at the front plate.

4. A finder having a rotary front plate, a back plate pivoted to the front plate, a top plate pivoted to the back plate, means to detachably hold said pivoted parts in

dual positions, a stationary gear on or near the front plate, a diaphragm supporting frame, means on said frame whereby it will be supported and controlled during rotation 5 and a gear connected with the diaphragm frame adapted to rotate with it and which meshes into the stationary gear at the front plate.

5. A finder having a rotary front plate, a 10 back plate pivoted to the front plate, a top plate pivoted to the back plate, means to detachably hold said pivoted parts relative to the front plate, a stationary gear on or

near the front plate, a diaphragm supporting frame, a gear connected with the dia- 15 phragm supporting frame adapted to ro- tate with it and which meshes with the sta- tionary gear at the front plate, an annular groove in the diaphragm supporting frame, and a pair of rods supported upon the top 20 plate which engage in said groove at oppo- site sides of the diaphragm supporting frame.

In testimony whereof I have signed my name to this specification.

JOHN F. POLHEMUS.
